COMBINATION FOOD MERCHANTISING
CONTAINER AND COOKING UTENSIL

Milton W. Wishnick, Oak Park, Ill.

Application October 8, 1948, Serial No. 149,022

Term of patent 14 years

(Cl. D44—1)

To all whom it may concern:

Be it known that I, Milton W. Wishnick, a citizen of the United States, residing at Oak Park, in the county of Cook and State of Illinois, have invented a new, original, and ornamental Design for Combination Food Merchandising Container and Cooking Utensil, of which the following is a specification, reference being had to the accompanying drawing, forming a part thereof.

In the drawing:

Figure 3 is an end elevation viewed in the direction of the handle equipped end; and

I claim:

The ornamental design for a combination food merchandising container and cooking utensil, substantially as shown.

MILTON W. WISHNICK.
